UNITED STATES PATENT OFFICE.

WILLIAM S. HENRY, OF NEW YORK, N. Y., ASSIGNOR TO GENERAL RAILWAY SIGNAL COMPANY, OF GATES, NEW YORK, A CORPORATION OF NEW YORK.

CIRCUIT-CONTROLLER.

1,332,215.

Specification of Letters Patent.

Patented Mar. 2, 1920.

Application filed December 26, 1916. Serial No. 139,022.

To all whom it may concern:

Be it known that I, WILLIAM S. HENRY, a citizen of the United States, and a resident of the city of New York, in the county of 5 New York and State of New York, have invented a new and useful Circuit-Controller, of which the following is a specification.

This invention relates to circuit controllers for operating and closing electric circuits, and more particularly to such circuit controllers which are opened and closed by railway switches and the like.

One of the principal objects of this invention is to provide a circuit controller which 15 will be positive in its action, both in opening and in closing circuits; which can be easily, positively and accurately adjusted; and which is so inclosed and protected that it may be used for outside work.

20 A further object of the invention is to design and construct a circuit controller of the type mentioned, so that contacts thereof will be opened at the beginning of the angular movement of an operating shaft and will 25 not be again closed until said shaft has almost completed its angular movement.

A further object of the invention is to 30 design and construct a circuit controller so that the parts thereof may be adjusted easily and accurately to make the operation of the contacts occur after any desired angular degree of movement of the operating shaft.

Other objects and advantages will appear 35 as the description of the invention progresses, and the novel features of the invention will be particularly pointed out in the appended claims.

In describing the invention in detail, reference is made to the accompanying drawing, 40 in which is illustrated one preferred physical embodiment of the invention, in which like reference characters designate corresponding parts in the several views, and in which:

45 Figure 1 is a plan view of a device embodying my invention with the cover thrown back; Fig. 2 is a longitudinal cross sectional view upon the line 2—2 in Fig. 1 viewed in the direction indicated by the arrows *a*, and 50 showing the crank arm moved to one of its operated positions and the corresponding pair of contacts closed and the cover in its closed position; Fig. 3 is a fragmentary view

taken on the line 3—3 in Fig. 1 viewed in the direction indicated by the arrows *b* and 55 showing the crank arm moved to another of its operated positions and the corresponding pair of contacts closed; Fig. 4 is a view similar to Fig. 3 showing the crank arm in its middle position and the contacts in their 60 neutral or open position; Fig. 5 is a detail side view of one of the operating cams with part of the casing removed to show more clearly the construction of the parts by means of which said cam is adjusted on the 65 shaft.

Referring to Figs. 1 and 2 of the drawing, the mechanism embodying the invention is shown as inclosed in a suitable casing 1, said casing 1 having apertured lugs 4, 5, and 6 70 by means of which the casing may be firmly attached to any suitable support or standard. Both sides of the casing 1, have openings 7 and 8 formed therein, through which wires of the various circuits to be controlled 75 may be led. As it cannot always be known beforehand through which side it will be most convenient to pass the wires; a plate 9 and a conduit cap 10 are supplied, either of which is adapted to be fastened by means of 80 bolts 11, 12, 13 and 14 to either side of the casing 1. If the wires are brought in from the lefthand side, the conduit cap 10 will be fastened to the lefthand side as shown, and the plate 9 will be fastened to the righthand 85 side, but if the wires are brought in from the righthand side, the plate 9 and the conduit cap 10 will be interchanged. Of course, it is obvious that the wires may be brought in from both sides of the case and 90 in which case another conduit cap would be used in place of the plate 9.

A cover 15 is provided for closing the top 95 of the casing 1. This cover is pivoted by means of a pin 16 passing through a lug 17 on the cover 15, and through lugs 18 and 19 outstanding from the casing 1 at its rear end. A packing or gasket 20 is placed in a groove 21 which extends completely around the cover 15, and is so situated that when 100 the cover 15 is placed in its closed position, as shown in Fig. 2, the gasket 20 rests upon the upper edge of the casing 1. A groove 22 is also formed transversely of the cover 15 and is so positioned that the gasket 20¹ 105 therein rests upon a contact cover 23 which

fits closely against both sides of the casing 1 and extends transversely therebetween.

A pin 24 supported by lugs 25 and 26 on the casing 1 is provided for fastening a hasp link 27 to the casing 1. The other end of the hasp link 27 is curled about a pin 28 which is fastened in a hasp 29. The hasp 29 has a longitudinal slot therein which is arranged to receive an apertured lug 30, 10 which is either cast integral with the cover 15 or fastened rigidly thereto.

By placing the cover 15 in the closed position as shown in Fig. 2, and then swinging the hasp 29 into the position as shown in Fig. 2, considerable pressure is exerted by the hasp 29 to force the cover 15 down tightly upon the casing 1 thereby compressing the gasket 20 and forming a water tight joint entirely around the top edge of the casing 1 and also along the cover plate 23 so that chamber 31 is protected from water either at the junction between the cover 15 and the top edge of the casing 1 or between the cover 15 and the top edge of the cover plate 23. By inserting a padlock in the hole 30¹ in the apertured lug 30, the cover may be locked in the closed position.

The casing 1 has a rib 32 rising from the bottom thereof and ribs 33 and 34 projecting from the sides thereof. These ribs have holes therethrough to receive bolts, 35, 36, and 37 by means of which a contact panel 38, made of any suitable insulated material, is firmly attached thereto, and is drawn so tightly against the ribs 32, 33 and 34 that for all practical purposes a water tight joint is formed, thus completing the isolation of chamber 31 from outside moisture.

The construction as above described provides a water tight chamber 31 and a chamber 39 which is almost water tight depending upon the tightness of the joint between the conduit cap 10 and any conduit to which it is connected. It will, however, be apparent that trouble is not so likely to occur from water or moisture in chamber 39, as in chamber 31, there being no operating contacts to corrode and the wires which enter this chamber 39 through the hole 8 are all securely connected to binding posts 40, 41 and 42, hereinafter more fully described, and are therefore not so liable to become sufficiently corroded as to interfere with their electrical conductivity. Chamber 31 is, however, made thoroughly water tight because the movable contacts of the circuit controller are located therein, as will be later described, and because, as is well known to those skilled in the art, all contacts which are made and broken at intervals must be retained in a bright, untarnished and electrically conducting condition.

Although the construction above described prevents the entrance of moisture or water 65 into the chamber 31, it does not prevent the

condensation of moisture upon the under side of cover 15. Heretofore such condensed moisture forming upon the under side of cover 15 has been a source of considerable annoyance, because after condensing, it 70 forms drops which fall upon the contacts 46, 47 and 48, cause them to tarnish and so destroy their power of conducting electricity or at least, greatly increases the resistance at the points of contact. A remedy for such 75 difficulty has been provided in the cover plate 23, which is pivoted on pins 49 and 50 fastened in the opposite sides of the casing 1. The cover plate 23 is prevented from becoming displaced by means of the cotter pins 51. The cover plate 23 extends over all 80 of the contact springs when in the position shown in Fig. 2, consequently any moisture which may collect on the under side of the cover 15 and then drop, is prevented from 85 falling on the contacts 46, 47 and 48. Furthermore, the changes in temperature outside of the casing 1 will not cause a condensation of moisture on the under side of cover plate 23, by reason of the fact that 90 there is a body of air between the cover plate 23 and the outside cover 15.

By referring to Fig. 1, it will be seen that the panel 38 has mounted thereon a series of contact groups arranged in rows, each 95 of said rows constituting a contact group, comprising a pair of fixed contact fingers and a movable contact arm. Each of said contact groups is capable of controlling certain electric circuits and is so constructed 100 that they may be operated jointly, in a manner hereinafter more fully explained, and since all of these contact groups are the same a description of one will suffice for all.

Included in each of the above contact 105 groups and supported by the contact panel 38 are binding posts 40, 41 and 42. Each of these binding posts include a bolt which extends through the contact panel 38 and holds the brackets 43, 44 and 45, respectively, 110 tightly against the contact panel 38 and also makes electrical connection with such brackets, thus serving as a means to conduct electricity from one side of the panel 38, that is the side exposed to chamber 39, 115 to the other side of the said panel 38, that is the side exposed to the chamber 31, and at the same time to offer no opportunity for water or moisture to pass from one chamber to the other.

The bracket 45 bears a resilient contact arm 46 which may be, by means herein-after described, moved from contact with a contact spring 47, supported by bracket 44, shown in Fig. 2, into contact with a contact spring 48, supported on bracket 43, shown in Fig. 3, or said arm 46 may be moved to a middle or neutral position. When speaking of the contact springs 47 and 48 hereinafter, the contact spring 47 125 130

will be termed the reverse contact and the contact spring 48 will be termed the normal contact.

Extending transversely of the contact arms 46 are two insulating blocks 52 and 53. These blocks are of suitable insulating material located one on each side of the contact springs 46 and supported thereon by means of dowel pins 54 (see Fig. 2) which pass through a hole in each of said contact arms 46 and into holes adapted to receive them in each of the insulating blocks 52 and 53. The contact springs 46 fit into slots formed in the inner faces of said insulating blocks, and these slots are so formed that although the insulating blocks 52 and 53 may be tightly pressed together at the top, the contact arms 46 may still aline themselves without cramping when moved from one position to the other position.

One end of a guide arm 56 is securely fastened to the insulating blocks 52 and 53 by means of bolts 57 and 58, said bolts also acting to hold the insulating blocks 52 and 53 tightly clamped together. The other end of the guide arm 56 is bifurcated and has two flat bearing surfaces or guides 56¹ and 56², best shown in Fig. 2, which are adapted to bear on a cylindrical collar 59 fitted on a square shaft 60. The guide arm 56 has journaled on opposite sides thereof, by means of a pin 61, two rollers 62 and 63.

These rollers 62 and 63 are so located that they lie respectively in the paths of movement of the cam shells designated generally by 64 and 65. The cam shell 64, best shown in Figs. 1 and 2, has two separate curved flanges 66 and 67, supported from the body portion 68 of the cam shell 64, by means of radial ribs 69, forming, respectively, separate cam faces 66¹ and 67¹ adapted to coact with the roller 62, as will be hereinafter more fully explained. The cam shell 65 is similar in construction to the cam shell 64 and also has two curved flanges 70 and 71, which are supported from the main body portion 72 by means of the radial ribs 73, and which form as in the case of cam shell 64, separate cam faces 70¹ and 71¹ adapted to coact with the roller 63. By referring to Figs. 2 and 4, it will be seen that each of the cam shells 64 and 65 have a long and a short cam face but that the cam faces on the cam shell 65 are reversely arranged as compared with the cam faces on the cam shell 64. These cam faces are also, for reasons to be later more fully explained, of different radial distances from the centers of their respective cam shells. Referring to Fig. 5, it will be seen that the cam faces 70¹ and 71¹ on the flanges 70 and 71 respectively, are slightly cut away or beveled, as at 74 and 75, respectively, so as to provide a clearance for the roller 63 when one of said cam faces is about to disengage said roller and the

other of said cam faces is about to engage it. The cam faces 66 and 67 of the cam faces 66¹ and 67¹ are also cut away or beveled, as shown in Fig. 2 and indicated by 76 and 77 respectively, for a clearance for roller 62.

70

The square shaft 60 extends transversely of the casing 1 and on either end has bushings 78 which are supported in the bosses 79 formed integral with the sides of the casing 1. This shaft bears at intervals the two drivers 80 (see Fig. 5) which have teeth cut about their entire periphery. These drivers 80 form a part of two adjustable cams and since their construction is the same a description of one is considered sufficient. The teeth of the driver 80 engage with a worm wheel 81 which is journaled in a clamp 82, said clamp 82 being pivoted on a pin 83 supported by the walls of the cam shell 64. A bolt 85 passes through the apertures of the lug 84 and the end of the clamp 82, so that by means of the nuts 86, the clamp 82 may be held firmly in a given position relative to the lug 84, and since the worm wheel 81 is journaled in the clamp 82 and bears against the driver 80, it may be clamped so firmly against the driver 80 that it cannot be turned by means of a screw driver inserted in a slot 87. In order to allow the cam shell 64 to rotate relatively to the shaft 60, when desired, bushings 88 have been placed upon the shaft 60, and the cam shell 64 has been made to bear upon their outer circular periphery.

125

130

The normal position of the shaft 60 would, if the cam shell 64 were rigidly attached thereto, determine the exact position of the cam faces on the flanges 66 and 67, but as different conditions require different operations of a circuit controller, it is necessary to provide an adjustment between the shaft 60 and the cam shell 64. This adjustment is provided by the parts just described in connection with the driver 80, the worm wheel 81, the clamp 82 and the bolt 85. If the position of cam shell 64 for the particular situation is not as it should be, then in order to adjust it, it is merely necessary to loosen the nuts 86, thereby loosening clamp 82, which allows the worm wheel 81 to be freely turned by means of a screw driver inserted in slot 87. As the driver 80 cannot rotate about shaft 60 a turning of the worm wheel 81 will cause a rotation of cam shell 64, as has been explained, about the axis of the shaft 60. When the desired position of the cam faces 66¹ and 67¹ on the flanges 66 and 67 has been reached, the nuts 86 are tightened, thereby causing clamp 82 to clamp the worm wheel 81 tightly against the driver 80 so that all parts will remain permanently in the adjusted position.

This method of adjustment, it should be observed, is extremely precise, so that a very minute change in the cam surfaces may

be readily made, and at the same time it is very strong and substantial. The connection between the driver 80 and the cam shell 64 is such that the cam shell 64 will be forced to move with the driver 80 even if after making an adjustment, by loosening nuts 86, the person so doing neglects to tighten the said nuts. As the means for adjustment are the same for cam 65 as described for cam 64 it is considered that a description of one will suffice for both and the means herein described for the adjustment of the cams is the same as that shown and described in the Patent Number 1,162,693, granted to W. S. Henry, November 30, 1915.

The shaft 60 is operated by a crank arm 89, which is pinned to one end of the shaft 60 outside of the casing 1, best shown in Fig. 1, so that a movement of the crank arm 89, by any suitable means, causes a movement of the circuit controllers within the casing 1. The other end of the shaft 60, which extends outside of the casing 1, is protected by means of a shield 90 which is pinned to the shaft 60. Endwise movement of the shaft is prevented by means of the shield 90 on one side, the crank arm 89 on the other side and the cotter pins 91 within the casing 1.

By referring to Figs. 3 and 4, of the drawings, it will be apparent, from the description of the adjustment of the cam faces 66¹, 67¹, 70¹ and 71¹ about the axis of the shaft 60 previously given, that it is possible to adjust the said cam faces so that they will coat with the rollers 62 and 63 and cause the contacts, 46, 47 and 48 to respond to practically any desired angular degree of movement of the crank arm 89.

With all of the parts in the position as shown in Fig. 2, the contact arm 46 makes contact with the contact spring 47. If the crank arm 89 is moved toward the normal position, that is in the direction indicated by the arrow *c*, the cam shell 64 will be rotated in a clockwise direction and the cam face 66¹ will be moved out of engagement with the roller 62. As soon as the cam face 66¹ is moved out of engagement with the roller 62, the guide arm 56, which is fastened to the contact arm 46 and carries the rollers 62 and 63, as before described, will be free to be moved in the direction indicated by the arrow *d*, in Fig. 2. As the crank arm 89 continues to move, in the direction indicated by the arrow *c*, the cam face 67¹, on the cam shell 64, will engage the roller 63 causing the guide arm 56, guided by its bearing surfaces 56¹ and 56² which bear on the collar 59, to be moved in the direction indicated by the arrow *d* until the roller 63 touches the cam face 70¹ on the cam shell 65. The contact arm 46 will thus be moved out of contact with the con-

tact spring 47 and the circuit which may have been closed by the coating of the two last mentioned contacts will be interrupted.

Should the crank arm 89 be moved continuously from one of its extreme positions to the other of said extreme positions, or in other words, from the position as shown in Fig. 2, of the drawings, to the position as shown in Fig. 3, the guide arm 56, through the medium of the rollers 62 and 63 acted upon by the cam faces 67¹ and 70¹ respectively, will hold the contact spring 46 in an intermediate position, or, a position corresponding to that shown in Fig. 4, until the cam shell 65 has been rotated far enough for the cam face 70¹ to be moved out of the path of the roller 63 and at which time the roller 63 will be engaged by the cam face 71¹, on the cam shell 65, causing the guide arm 56 to be moved farther in the direction indicated by the arrow *d* until the contact arm 46 comes into contact with contact 48.

It will therefore be apparent that the contact arm 46 will break contact with contact 47 after a very slight movement of the crank arm 89 and thereafter during the remainder of the movement of the crank arm 89 will be held positively open and will not make contact with the contact spring 48 until the crank arm 89 has nearly completed its movement. Should the crank arm 89 be stopped in any intermediate position in its travel from one extreme position to the other of said positions, it will be apparent that the contact arm 46 will be held positively in its intermediate or neutral position, as shown in Fig. 4, of the drawings.

A circuit controller of the kind embodied in this invention is specially adapted for use in railway signaling systems to control such signal circuits which it is desired to have opened or closed in the normal, the intermediate or the reverse positions of railway switches. It is a well-known fact that railway switches are usually guarded by signals and it is desirable, for obvious reasons, that, while a switch is being moved from the normal to the reverse positions, or vice-versa; or while said switch is in any intermediate position, the signal guarding said switch should be placed in the danger position and it should be impossible to change said signal from the danger position until said switch has been moved far enough in a given direction to assure the safe passage of a train thereover. The above conditions may be satisfied by the use of a circuit controller of the kind embodying this invention, the crank arm of which is connected directly to the switch points by a rod or other suitable means, since the circuits, which are desired to be opened and closed, may be opened and closed at any desired position of the switch points.

From the foregoing description and application of principle, it can be seen that if anything happens to prevent a perfect or complete operation of the switch or other device operating the circuit controller, the defect will be indicated by opening the circuits controlled thereby.

The complete mechanism heretofore described will be perceived to contain elements rendering it positive in action; easily adjustable through a very wide range; and of such a nature that the parts will readily remain in an adjusted position. It will further be noticed that there are comparatively few operating parts, making it easily constructed and inexpensive to manufacture.

Although I have particularly described the construction of one physical embodiment of my invention and explained the operation and principle thereof, nevertheless I desire to have it understood that the form selected is merely illustrative and does not exhaust the possible physical embodiments of the idea of means underlying my invention.

What I claim as new and desire to secure by Letters Patent of the United States, is:

1. In a three-position circuit controller, a movable contact element, an operating shaft, a guide arm connected at one end to said contact element and guided at its other end by said shaft, two cams attached to said shaft and relatively adjustable thereon, each of said cams having a long and a short cam face substantially concentric with the axis of the operating shaft and at different radial distances therefrom, the long cam faces of said cams being in part co-extensive around the shaft and at different distances therefrom, and two rollers carried by said guide arm and co-operating separately with the faces of said cams.

2. In a three-position circuit controller, a movable contact element, an operating shaft, a guide arm connected to said contact element at one end and guided at its other end by said shaft, two rollers carried by said guide arm and projecting from opposite sides thereof, and two cams adjustably secured to said shaft and disposed on opposite sides of the guide arm, each of said cams having a long and a short face substantially concentric with and at different radial distances from the axis of the operating shaft, the long faces of said cams being in part co-extensive around the shaft, said cams co-acting separately with said rollers to control the movement of the guide-arm from a corresponding extreme position to its middle position.

3. In a three-position circuit controller, a movable contact element, an operating member connected to said contact element and insulated therefrom, two rollers carried by said member and projecting from opposite sides therefrom, an operating shaft, and two

cams carried by said shaft and co-operating with said rollers separately to shift said operating member from a corresponding extreme position to a middle position, each of said cams having two laterally projecting curved flanges forming concentric long and short cam faces at different radial distances from the axis of the operating shaft, said cams having their long cam faces extending in part through overlapping angles one inside the other to engage their respective rollers simultaneously on opposite sides thereof.

4. In a three-position circuit controller, a movable contact element, an operating shaft, a guide arm connected at one end to said contact element and guided at its other end by said shaft, and cams separately adjustable around the operating shaft for reciprocating said guide arm.

5. In a three-position circuit controller, a movable contact element, an operating shaft, a guide arm connected to said contact element and guided by said shaft, co-axial rollers carried by said guide arm and projecting from opposite sides thereof, and two cams adjustably mounted on said shaft and co-operating with said rollers separately.

6. In a three-position circuit controller, a movable contact element, an operating member connected to said element and insulated therefrom, two rollers carried by said operating member and projecting from opposite sides thereof, an operating shaft, and two cams arranged side by side on said shaft co-operating separately with said rollers.

7. In a circuit controller, a movable contact element, a roller operatively connected to said contact element, an operating shaft, and a cam secured to said shaft and having long and short faces of different radii concentric with the axis of said shaft, said cam faces acting against opposite faces of the roller in different positions of the operating shaft.

8. In a three-position circuit controller, a movable contact element, an operating shaft, two cam shells relatively adjustable on said shaft and each having long and short laterally projecting curved flanges supported by radial ribs, said flanges having different radii concentric with the axis of said shaft, the long flanges of the respective cams being in part co-extensive around the shaft, and means acted upon in opposite directions by the flanges of the respective cams for operating said contact element.

9. In a three-position circuit controller, an oscillatory operating shaft, a cylindrical collar on said shaft, a guide arm having one end bifurcated and guided by said collar, rollers carried by said guide arm and projecting from opposite sides thereof, two cams attached to said shaft and relatively adjustable thereon, said cams being ar-

ranged on opposite sides of said collar and being adapted to coöperate separately with said rollers, and a movable contact element connected to said guide arm.

5 10. In a three-position circuit controller, a movable contact element, an oscillatory operating shaft, two cams relatively adjustable on said shaft, each of said cams

having long and short cam faces of different radii concentric with the axis of said shaft, 10 and operating means connected to said contact element, said cams being arranged with their respective long and short faces acting upon said operating means in opposite directions.

WILLIAM S. HENRY.
